UNITED STATES PATENT OFFICE.

JOHN W. BROWN, OF TRENTON, NEW JERSEY, ASSIGNOR TO THE GRIEB RUBBER COMPANY, OF SAME PLACE.

DESIGN FOR A BOOT OR SHOE HEEL.

SPECIFICATION forming part of Design No. 32,140, dated January 23, 1900.

Application filed October 30, 1899. Serial No. 735,320. Term of patent 14 years.

To all whom it may concern:

Be it known that I, JOHN W. BROWN, a citizen of the United States, and a resident of Trenton, New Jersey, have invented a new and original Design for a Heel for Boots or Shoes, of which the following is a specification.

My design for a boot or shoe heel is fully shown in the accompanying drawing, which represents a perspective view of the heel inverted and drawn to an enlarged scale.

The design comprises a series of rosettes disposed parallel with the edges of the heel and alternating with openings, each of the rosettes consisting of a central teat or boss surrounded by a raised ring and each of the openings being also surrounded by a similar ring.

In the drawing, 1 represents the rosettes, each consisting of a central boss 2 and surrounding raised ring 3, and 4 represents the openings or depressions, each surrounded by a raised ring 5.

Having thus described my invention, I claim and desire to secure by Letters Patent—

The design for a boot or shoe heel, substantially as described and as shown in the accompanying drawing.

In testimony whereof I have signed my name to this specification in the presence of two subscribing witnesses.

JOHN W. BROWN.

Witnesses:

F. E. BECHTOLD,
JOS. H. KLEIN.
